UNITED STATES PATENT OFFICE.

HARRY B. WHITE, OF CANTON, OHIO, ASSIGNOR TO THE GILLIAM MANUFACTURING COMPANY, OF CANTON, OHIO, A CORPORATION OF OHIO.

BOW REST AND CLAMPING DEVICE.

1,285,517.

Specification of Letters Patent. Patented Nov. 19, 1918.

Application filed January 22, 1916. Serial No. 73,621.

To all whom it may concern:

Be it known that I, HARRY B. WHITE, a citizen of the United States, residing at Canton, in the county of Stark and State of Ohio, have invented a new and useful Bow Rest and Clamping Device, of which the following is a specification.

This invention relates to a device for supporting and clamping the bows of a vehicle 10 top in a folded position.

The object of my invention is, to provide an improved bow rest and clamping device which may be readily attached to a vehicle and which may be adjusted for folding tops 15 of various sizes.

A further object is to provide a simple, inexpensive and efficient device of the character referred to.

With these objects in view the invention 20 consists in the novel construction and arrangement of parts, hereinafter described, illustrated in the accompanying drawings, and particularly pointed out in the appended claims, it being understood that 25 various changes in the form, proportions, size and minor details of construction may be made within the scope of the appended claims, without departing from the spirit or sacrificing any of the advantages of the 30 invention.

In the drawing:

Figure 1 is a side elevation of a bow rest embodying my invention.

Fig. 2 is a rear elevation of the same.

Fig. 3 is a vertical longitudinal section 35 of the same.

Fig. 4 is a section on the line 4—4, Fig. 3.

Fig. 5 is a fragmentary elevation of the upper portion of a bow rest provided with 40 a slightly modified form of clamping member.

Similar numerals of reference indicate corresponding parts throughout the several figures of the drawings.

In the drawings the numeral 1 indicates a 45 channel member which is provided with the upper and lower walls 2 and 3 respectively, and with the socket 4, said socket being preferably split as best illustrated in Fig. 2 and 50 provided with a clamping screw 5, the socket being adapted to receive the extremity of the usual bracket provided upon the bodies of automobiles and similar vehicles, the screw 5 being for the purpose of retaining 55 the bow rest upon said bracket.

The lower extremity of the channel member 1 is provided with a horizontal arm 6, preferably formed integral therewith, a concaved rest 7 being formed upon said arm, said rest being covered with a pad 8 of 60 leather or similar material which may be attached thereto, as by rivets 9, thus forming a rest upon which the lowermost bow of the top will be located when the top is in the folded position.

Vertically disposed apertures 10 and 11 are provided in the upper and lower walls 2 and 3 respectively of the channel member 1, and the clamping rod 12 is slidably mounted through said apertures. The upper end of the rod is preferably bent or curved outwardly to form a clamping member 13, the inner surface of which is provided with a pad 14 of the usual form of 70 construction.

The lower extremity of the rod 12 is screw threaded as indicated at 15, an internally screw threaded collar 16 being provided upon said screw threaded portion of the rod and adapted to contact with the upper surface of the lower wall 3 of the channel member. A wing nut 17 is provided upon the lower extremity of the rod 12 and interposed between said wing nut and the wall 3 of the channel member is located a 75 resilient member 18, preferably in the form of a split spring washer. The vibration of the car would ordinarily tend to cause the wing nut 17 to work loose upon the screw threaded portion of the rod 12 and in order 80 to prevent this the split spring washer 18 is provided between the wing nut and the lower wall of the channel member as above mentioned.

In Fig. 5 is illustrated a slightly different 95 form of clamping member, the upper end of the clamping rod 12^a being preferably bent outwardly to form a horizontal arm 19 on which is adjustably mounted the clamp 21. This clamp preferably comprises a collar 100 which is mounted in any suitable manner for rotation upon the arm 19, and the curved plate 20 formed integral therewith and arranged in an inverted position. A pad 22 of leather or equivalent material is provided 105 upon the inner curved face of the clamp.

I claim:

1. In a device of the character described, the combination of a channel shaped supporting member having a rest arranged to 110

support the bows of a vehicle, a rod slidably mounted within said channel shaped member and provided with a clamp arranged to coöperate with the rest to support the bows, 5 upper and lower end walls provided upon said channel shaped member and arranged to support said rod adjacent its upper and lower ends, an adjusting collar carried by said rod and located within said channel and 10 a clamping device mounted upon said rod and arranged to coöperate with the collar to draw the rod downwardly and tightly secure it to the channel member.

2. In a device of the character described, 15 the combination of a channel shaped supporting member having a rest arranged to support the bows of a vehicle, a rod slidably mounted within said channel shaped member and provided with a clamp arranged to co- 20 operate with the rest to support the bows, upper and lower end walls provided upon said channel shaped member and arranged to support said rod adjacent its upper and lower ends, and a nut upon said rod below 25 the lower wall and adapted to draw said rod downwardly and securely clamp the bows between said clamp and said rest.

3. In a device of the character set forth, 30 the combination of an elongated stock having a vertical passage therethrough with bearings at the upper and lower end-portions thereof, said stock having body-attaching means and having, also, a laterally project-

ing bow-support at its lower end-portion, a rod slidably housed in said stock and having 35 a projecting upper end equipped with a laterally-projecting bow-clamp, and an adjusting nut on the lower end of said rod engaging the bearing at the lower end of said stock, said nut being accessible below the 40 plane of said bow-support and adapted to draw said rod downwardly and clamp the bows between said bow-clamp and bow-support.

4. In a device of the character set forth, 45 the combination of an elongated stock having a vertical passage therethrough, with bearings at the upper and lower end-portions thereof, said stock having its upper portion equipped with body-attaching means 50 and having its lower portion equipped with a laterally-projecting bow-support, a rod slidable in said stock having its upper end equipped with a laterally-projecting bow- 55 clamp, and an adjusting nut on the lower end of said rod disposed below the lower end of said stock and engaging the bearing thereat, said nut being located below the plane of said bow-support and accessible beneath said stock and adapted to draw said rod downwardly and clamp the bows between said bow-clamp and bow-support.

In testimony that I claim the above I have hereunto subscribed my name.

HARRY B. WHITE.
